UNITED STATES PATENT OFFICE.

EDWIN F. GUTH, OF ST. LOUIS, MISSOURI.

LIGHTING FIXTURE.

Application filed February 17, 1926. Serial No. 88,758.

My invention relates to that class of lighting fixtures in which a reflector canopy is employed to direct the rays of light downwardly to the working plane.

5 My invention has for its object, to provide a unitary construction which will completely enclose the light or lamp bulb, thus effectually preventing particles of dust and dirt or insects collecting in the enclosing 10 bowl and thus interfering with the passage of the lumines emitted by the lamp, and in this manner lowering the efficiency of the unit.

15 My invention has for its further object to provide such a mounting for the canopy reflector that the relationship to the lamp may be adjusted vertically, and to so construct the canopy that it can be used to direct the light rays to either or both ceiling and working plane.

20 My invention has for its further object to so shape the contour of the globe, as to produce lowest brightness in the lower portion which is most visible and closest to the filament at the side which permits the greatest 25 volume of light to pass through it at this point for the reason that there is less opaque material around the filament at this point and that the light rays strike this surface 30 in a direct direction.

35 A further object is to position the lamp filament high so as to produce the low brightness at the source, very wide light distribution curve, and the combination will 40 function in efficiency practically the same as the regular enclosing globes in overall output or efficiency, and will produce a much wider light curve, by photometer test, than diffusing globes alone, which controls the 45 light rays with less on the ceiling and correspondingly greater portion on a plane slightly below the horizontal, and lower brightness at the source than most of the enclosing globes of the same dimensions.

45 This construction gives my unit this added advantage, as shown by the photometric chart of the light curve of very low intensity directly above the fixture and gradually increasing in intensity to a position about 50 35 degrees below the horizontal and maintaining a substantially uniform intensity beneath that point.

55 My means for accomplishing the foregoing objects may be more readily understood by reference to the accompanying drawings in which

Fig. 1 is a side elevation, a portion being broken away to show the interior;

Fig. 2 is an enlarged detail view showing the adjustment means provided whereby the 60 reflector canopy may be vertically adjusted;

Fig. 3 is a side elevation, a portion being broken away, showing a modified form of reflector canopy;

Fig. 4 is a view on the line 3—3 in Fig. 65 3 in the direction indicated by the arrows.

Similar reference numerals refer to similar parts throughout the entire description.

As shown in the drawings, the light or lamp bulb is mounted in the conventional 70 socket 2 which is preferably the standard porcelain keyless type. It is mounted in a standard fitter 3 being secured therein by means of a nipple carried by an eye 4 by which the unit may be suspended by means 75 of a chain 5 (only a portion of one link thereof being shown). The periphery 6 of the fitter 3 is provided with the usual thumb screws 7, the inner ends of which engage the lip 8 formed on the neck 12 of the globe 9.

80 The configuration of this globe 9, as will be obvious to persons skilled in the art, is such that it will produce lowest brightness in the lower portion which is most visible and closest to the filament at the side which permits the greatest volume of light to pass 85 through it at this point for the reason that there is less opaque material around the filament at this point and that the light rays strike this surface in a direct direction, and will redirect many of the light rays to the 90 under surface of the reflector canopy 10. This canopy reflector 10 is constructed with a downwardly and inwardly tapering portion 11, which is fitted to, and coincides with, the exterior surface of the neck 12 of the globe 9. Both the upper and lower surfaces of the reflector canopy 10 are finished so 95 that they will function in the best possible manner as a reflector. The canopy reflector 10 is preferably stamped from sheet metal, and three fingers 13, 14 and 15 are formed, extending inwardly from the opening in the center. These fingers may be provided with any desired number of openings. As illustrated, there are two, 16 and 17, so that the 100 vertical position of the canopy reflector 10 may be changed or adjusted, for the fingers 13, 14 and 15 are bent up into the position clearly shown in Figs. 1 and 3. The openings 16 or 17 in the fingers will permit the 105 screws 7 to pass through. As shown in the 110

drawings, the screws extend through the openings 16, with the result that a large number of the direct rays of light emitted by the lamp 1, will impinge upon the upper 5 surface of the reflector canopy 10, whence they will be redirected or reflected to the ceiling, and in this way it will be satisfactorily illuminated. The remaining light rays will strike the globe, some of them will 10 pass through and others will be redirected to the lower surface of the reflector canopy, whence they will be reflected to the working plane.

It will be apparent from the foregoing 15 description that the position of the reflector canopy 10 may be varied vertically, as shown in the dotted lines, to meet the desired conditions, since this adjustment will vary the amount of the reflecting surfaces 20 exposed to the light rays, and if the condition is such as to render it desirable, they may be entirely excluded from the upper surfaces and all of the light rays directed to the working plane.

25 It may be found desirable in practice, to meet certain conditions, to form the surface of the reflector canopy 10, as shown in Figs. 3 and 4, with a plurality of concentric or perhaps irregular undulations for the purpose of eliminating the specular reflections 30 of the globe 9 and the intensity of the lamp 1, but if this is done, it should be so slight, that they will not materially affect the distribution of the light rays.

35 It will be seen that I have only described the specific construction shown in the drawings, but I desire it to be understood that I reserve the privilege of utilizing all the mechanical changes to which the invention 40 is susceptible, my invention not being limited except as I have defined and limited it in the hereinafter contained claims.

Having thus described my invention what I claim is new and desire to secure by Letters Patent of the United States is:

45 1. The combination in a lighting fixture of a fitter, a globe having a convex lower

and a concave upper portion terminating in a neck, a lamp bulb in said globe, a socket mounted in said fitter, a reflector canopy 50 mounted in juxtaposition to the neck of said globe, and means to adjust said reflector canopy vertically.

2. The combination in a lighting fixture of a fitter, a globe having a neck which 55 flares downwardly and outwardly and joins a convex portion, whereby low intensity is produced on the lower convex portion and low absorption in the neck portion, a lamp bulb in said globe, a socket mounted in said 60 fitter, a reflector canopy mounted in juxtaposition to the neck of said globe, and means to adjust said reflector canopy vertically.

3. The combination in a lighting fixture of a fitter, a globe having an upwardly extending neck, a lamp bulb in said globe, a 65 socket mounted in said fitter, a reflector canopy formed with a downwardly and inwardly extending portion which is fitted to and coincides with the outer surface of said 70 neck, and means to adjust said reflector canopy vertically.

4. The combination in a lighting fixture of a fitter, a globe having an upwardly extending neck, a lamp bulb in said globe, a 75 socket mounted in said fitter, a reflector canopy formed with a downwardly and inwardly extending portion which is fitted to, and coincides with the outer surface of said 80 neck, and means to adjust said reflector canopy vertically, said means being formed integral with said canopy.

5. The combination in a lighting fixture of a fitter, a globe having an upwardly extending neck, a lamp bulb in said globe, a 85 socket mounted in said fitter, a reflector canopy mounted in juxtaposition to the neck of said globe, and means to adjust said reflector canopy vertically, said means comprising a plurality of fingers secured to said 90 canopy and means to adjustably secure said fingers to said fitter.

EDWIN F. GUTH.
